PLASTIC DOLL'S EYE AND METHOD OF
MAKING SAME

Richard Rupert, Independence, Mo.

Application March 24, 1947, Serial No. 736,784

2 Claims. (Cl. 46—165)

1

This invention relates to dolls' eyes and method of making same, and more particularly to a device shaped to form the eyes for dolls, toy animals and the like. Artificial eyes for dolls, toy animals, and for use in fur pieces and the like are usually made of glass or glass and metal pieces assembled on a pin for insertion in the body of the doll or the like. The eyes for the dolls receive rough usage, and children tend to pick at the eyes, and in dropping or otherwise playing with the doll the eyes are sometimes struck, causing breakage of the portion forming the eyeball, and quite often the glass and metal portions become separated showing the eye.

The objects of the present invention are, therefore, to provide a plastic eye of a plurality of colored pieces for dolls and the like; to provide a plastic head for a pin and the like to form an eye for use in dolls and toys; to provide a plastic head for a pin having a plurality of colored pieces assembled and formed into an integral structure; to provide a method of forming plastic parts of a doll's eye, applying same to the head of a common pin, assembling the parts, and shaping said assembly into an integral pinhead; to provide the method of forming a plastic eye whereby the cornea portion is of different color than the plastic forming the eyeball; and to provide a plastic doll's eye that is easily formed and which is characterized by its simple, unbreakable construction, economy of manufacture and attractive appearance.

In accomplishing these and other objects of the present invention, I have provided improved details of structure, the preferred forms of which are illustrated in the accompanying drawings, wherein:

Fig. 1 is a perspective view of a doll's eye embodying the features of the present invention.

Fig. 2 is a side elevation of the eye with the pin inserted in the doll or other structure.

Fig. 3 is a vertical sectional view through the plastic portions of the doll's eye, said portion being shown in disassembled relation.

Fig. 4 is a plan view of the ball portion of the eye showing the concentric recesses for receiving the cornea portion of said eye.

Fig. 5 is a vertical sectional view through the doll's eye illustrating the assembly of the parts thereof before the final forming operation.

Fig. 6 is a vertical sectional view through a doll's eye in a mold for reshaping the eye for retaining the cornea portion in place.

Referring more in detail to the drawings:

1 designates a plastic doll's eye consisting of 55 and of the desired color of plastic. Then the

2

an eyeball portion 2 having concentric therewith a cornea portion 3, preferably of contrasting color with the eyeball 2. The eye also includes a pin 4 for insertion into the head 5 of a doll, toy animal and the like.

The eyeball portion is molded of a suitable plastic, for example, cellulose acetate butyrate, which may be reshaped by suitable application of pressure after the ball is molded. The doll's eye preferably is constructed of a plurality of plastic members of different color, for example, the ball portion may be amber and the cornea portion black. The eyeball 2 is preferably molded of cellulose acetate butyrate, and in the illustrated form preferably has a flat face 6 terminating in a bevelled edge 7, the outer face 8 thereof being of substantially spherical contour. Located in the outer face and concentric therewith is a recess 9 of substantially half the depth 10 of the eyeball, the peripheral edges 10 and 11 of said recess converging or sloping toward the axis of the eyeball from the greatest diameter 12 of the recess which is spaced inwardly from the outer edge 13 thereof. A bore 14 concentric with 25 the eyeball and recess 9 extends through the eyeball and is of such diameter as to receive the shank 15 of the pin 4. The bottom face 16 of the recess 9 is provided with a counterbore 17, of suitable diameter to receive the head 18 of the pin 4, the depth of the counterbore 17 being substantially the same as the thickness of the head 18.

The cornea of the eye is molded separately and may be of any suitable material and is preferably of cellulose acetate butyrate and of a different color than the eyeball. The cornea 3 preferably has opposite faces 19 and 20 of substantially spherical contour, substantially of the same radius as the face 8 of the eyeball, the peripheral edge 21 being of a diameter substantially the same as the diameter 12 of the recess 9 and provided with bevelled faces 22 and 23 converging toward the axis of the cornea member, the bevel of the faces 22 and 23 being substantially the same as the faces 10 and 11 respectively of the recess 9. It is to be noted that the faces 19 and 20 and the bevels 22 and 23 are substantially the same, whereby the cornea is reversible, and the spacing between the faces 19 and 20 is such that 45 when the bevel 23 is seated on the bevel 11 of the recess 9, the face 19 will conform substantially to the contour of the face 8 of the eyeball portion. The members 2 and 3 are molded separately

and of the desired color of plastic. Then the

eyeball member 2 is seated in a recess 24 of a mold 25. The pin 4 may then be inserted in the member 2 in such a manner that the shank 15 extends through the aperture 14 into a suitable aperture 26 of said mold, the head 18 of the pin seating in the recess 17 of the eyeball member 2. The cornea is then placed on the edges 13 of the recess 9, for example the bevelled face 23 resting on the edge 13, and pressure applied to the face 19 of the cornea member to snap same into the recess 9, pressure being required to place the cornea in said recess due to the relative sizes of the cornea member and the diameter of the recess at the edge 13. When the cornea is snapped into the recess 9 and the face 23 resting on the face 11, a plunger 27 having a recess 28 therein of the contour of the finished eye is moved downwardly into engagement with the eyeball 2 and cornea 3 and pressure applied thereto to shape the eye 13 and force the bevelled face 10 of the member 2 into engagement with the edge 22 of the cornea 3, in such a manner that the face 8 and face 19 appear to be substantially continuous. After the shaping of the members 2 and 3, the plunger 27 is retracted and the eye member removed from the mold, the eye member then being ready for use in dolls, toy animals and the like.

It is believed obvious that I have provided an improved eye for dolls and the like that is substantially unbreakable, and provided with a sequence of method steps for forming same from a plurality of pieces of contrasting colors, yet present a smooth, integral appearance.

What I claim and desire to secure by Letters Patent is:

1. A doll's eye consisting of the combination of an oblate member of semitransparent plastic material to simulate the eyeball, said member having a concentric recess in the front face thereof, said recess terminating in an inwardly sloping seat portion, a plastic cornea member of different color seated in said recess, said cornea having

bevelled peripheral edges and curved opposite faces corresponding in curvature to the front face of the oblate member, one of said bevelled edges seating on the seat portion of the recess, the outer edges of said recess extending over and engaging the other bevelled edge of the cornea member to retain same in said recess, a pin having its head mounted in the oblate member, and a shank extending rearwardly thereof for securing the eye in a doll.

2. A doll's eye consisting of the combination of an oblate member of semitransparent plastic material to represent the eyeball, said member having a central bore therethrough and a plurality of counterbores therein forming recesses, the counterbore adjacent the front face of said eye being the larger and having an inwardly sloping frusto-conical seat portion at the inner end thereof, a pin having the head thereof in the counterbore remote from the front face and the shank extending through the bore of the eyeball member, and a plastic cornea member of different color seated in the larger counterbore, said cornea member having opposite faces of substantially spherical contour corresponding to the curvature of the oblate member, said faces terminating in frusto-conical peripheral edges one of which seats on the seat portion of the counterbore, the outer edge of the counterbore engaging the other frusto-conical peripheral edge of the cornea member to hold same in place with the curvature of the face of the cornea member forming a continuation of the curvature of the oblate member.
